UNITED STATES PATENT OFFICE

169,839

CLOSURE FOR COLLAPSIBLE TUBES

Christy M. Del Mas, New York, N. Y., assignor
to Grace-Mas Enterprises, Inc., New York, N. Y.,
a corporation of New York

Application August 19, 1952, Serial No. 21,113

Term of patent 14 years

(Cl. D58—26)

To all whom it may concern:

Be it known that I, Christy M. Del Mas, a citizen of the United States of America, residing at [redacted], [redacted], and State of New York, have invented a new, original, and ornamental Design for a Closure for Collapsible Tubes, of which the following is a specification, reference being had to the accompanying drawing, forming part thereof.

Figure 1 is a front elevation of a closure for collapsible tubes embodying my new design;

Figure 2 is a side elevation of the same; and

Figure 3 is a top plan view thereof.

I claim:

The ornamental design for a closure for collapsible tubes, as shown.

CHRISTY M. DEL MAS.
